CLAIM

The ornamental design for a pump bulb with multi-concavity faces for an implantable penile prosthetic, as shown and described.

DESCRIPTION

FIG. 1 is an isometric view of one embodiment of a pump bulb with multi-concavity faces showing a face of the pump bulb connected between two convex lobes of the pump bulb, where the face is both concave in lateral cross-section and concave in vertical cross-section.

FIG. 2 a front side view of the pump bulb with multi-concavity faces illustrated in FIG. 1.

FIG. 3 a back side view of the pump bulb with multi-concavity faces illustrated in FIG. 1.

FIG. 4 is a left side view of the pump bulb with multi-concavity faces illustrated in FIG. 1, where a right side view is not illustrated as it is a mirror image of the left side view.

FIG. 5 is a top side view of the pump bulb with multi-concavity faces illustrated in FIG. 1; and,

FIG. 6 is a bottom side view of the pump bulb with multi-concavity faces illustrated in FIG. 1.

In FIGS. 1-5 the broken lines illustrating conduits connected to the pump bulb form no part of the claimed design.

The broken line showing of conduits connected to the pump bulb and ribs on the faces is included for purpose of illustrating the environment and forms no part of the claimed design.

1 Claim, 4 Drawing Sheets
